UNITED STATES PATENT OFFICE.

JOHN LYTH, OF NEW YORK, N. Y.

FUEL-RECEPACLE.

SPECIFICATION forming part of Letters Patent No. 442,382, dated December 9, 1890.

Application filed May 31, 1890. Serial No. 353,890. (No model.)

To all whom it may concern:

Be it known that I, JOHN LYTH, a citizen of the United States, and a resident of New York, in the county and State of New York, have 5 invented a new and useful Improvement in Fuel-Receptacles, of which the following is a specification.

This invention relates to receptacles for fuel, such as coal, coke, and other fuels which 10 are handled by means of a shovel; and the object of the invention is to provide a receptacle in which the fuel can be closely confined, and which is practically dustless, and from which the fuel can be readily taken 15 from the bottom, and thereby the fine particles and dust can be gathered up with the larger lumps and fed to the fire.

In the accompanying drawings, Figure 1 represents a front elevation of my improved 20 fuel-receptacle; Fig. 2, a vertical section of the same; and Fig. 3, a modification thereof, showing in perspective the application of the receptacle to a stove or range.

Referring to the drawings, A represents the 25 body of the receptacle, which is preferably made of sheet-iron and may be cylindrical, as in Fig. 1, or square, as in Fig. 3, or of other suitable shape to adapt it to occupy any desired position in the room or about the stove, 30 range, or other heating or cooking apparatus. Preferably the bottom *a* of the receptacle is formed of a single casting with a flange *b*, over which the bottom edge of the receptacle is placed and riveted, as shown, and to give 35 strength and stiffness to the body a cast-metal rim *d*, with a suitable flange *e*, is placed on the top and secured by rivets, as shown. The top of the receptacle is also covered by a flat lid *D*, which may be provided with a suitable 40 handle sunk in, so that the top will form a flat surface on which articles can be placed.

At the bottom of the body A is formed a suitable opening E, in which is inserted and secured a chute F, through which the fuel is 45 taken from the receptacle. This chute is preferably made of cast metal in one or more pieces, as may be preferred. Its essential parts are a projection or guard *g*, extending from the top of the chute inward with a downward inclination, and the function of which 50 is to protect or guard the opening of the chute from choking by preventing the coal from

falling or settling directly downward into the chute; also, to sustain in part the weight of the coal, and thereby facilitate loading the 55 shovel. The bottom *G* of the chute projecting outward is curved upward forming a lip *h*, from which sides *i i* rise, and which are provided with outwardly-flared wings *k k*. The bottom *G* is also carried inward and forms 60 an inwardly-projecting lip *l*, that rests on the bottom of the receptacle, and, lapping over the joint between the chute and the bottom of the receptacle, gives free play and movement to the shovel when inserted under the 65 coal. The upper guard or projection *g* is provided with sides *m*, which strengthen the connection with the flange of the chute. The chute is provided with a flange or face-plate *II*, which is riveted to the receptacle, and thus 70 fastens the chute in place.

In Fig. 3 is shown a modification of the invention, consisting in making the receptacle of a general rectangular form and providing it with means by which it can be hung to the 75 side or back of a stove or range. To this end the receptacle is arranged to hang between the top and bottom flanges of the stove, as shown, suitable hooks or other devices being 80 provided to fasten it in place.

The receptacle may also be constructed to act as a measure where coal is bought by the bushel by providing it with a rib *r*, so placed that it indicates at a glance the quantity 85 when the fuel is placed in it.

The advantages of this invention are many. For example, by taking the coal or other fuel from the bottom of the receptacle it is more easily handled, less dust is produced, and the dust and small particles are gathered up together and fed to the fire. In taking the fuel 90 out on the shovel, if any loose lumps fall off, the flaring sides or wings *k k* catch them and deflect them back into the chute. The fuel is at all times covered up neatly and clean 95 and the receptacle is compact, occupying but little space.

I claim—

1. In a fuel-receptacle, the combination, 100 with a receptacle A, provided with an opening E at the bottom, of a chute F, inserted in said opening and provided with an inside guard *g*, substantially as specified.

2. A chute F for fuel-receptacles, consist-

ing of the interior projection or guard *g*, the bottom *G*, having the upwardly and outwardly curved lip *h* and the inwardly-projected lip *l*, and the flaring sides or wings *k*, substantially as described.

In testimony that I claim the foregoing as my invention I have signed my name, in pres-

ence of two witnesses, this 21st day of May, 1890.

JOHN LYTH.
